UNITED STATES PATENT OFFICE.

SAMUEL GOLDSTEIN, OF CHICAGO, ILLINOIS, ASSIGNOR OF ONE-FOURTH TO ISADORE GOLDSTEIN, ONE-FOURTH TO ABE GOLDSTEIN, AND ONE-FOURTH TO MEYER GOLDSTEIN, ALL OF CHICAGO, ILLINOIS.

BED DAVENPORT OR COUCH.

1,267,399.

Specification of Letters Patent. Patented May 28, 1918.

Application filed May 27, 1913. Serial No. 770,099.

To all whom it may concern:

Be it known that I, SAMUEL GOLDSTEIN, a citizen of the United States, residing at Chicago, Cook county, Illinois, have invented 5 certain new and useful Improvements in Bed Davenports or Couches, of which the following is a specification.

My invention relates to bed davenports or couches and the object thereof is to provide 10 furniture of this character with simple, efficient and easily operated mechanism for converting such furniture into a bed or couch. My present invention is intended as an improvement upon that described in my 15 prior application filed February 17, 1913, Serial No. 748,982. The various features of advantage and utility in my construction will be apparent from the description hereinafter given.

10 In the drawings Figure 1 is a sectional elevation of the davenport shown converted into a bed; Fig. 2 a sectional plan view of a portion of the parts illustrated in Fig. 1; Fig. 3 a sectional elevation of the davenport 15 in normal or closed condition; Fig. 4 a front elevation of one end of the davenport with a portion thereof broken away exposing certain operating parts; Fig. 5 a sectional elevation of the davenport showing the bed 20 sections and seat in the process of closing or opening; Fig. 6 an elevation viewed from the line 6—6 of Fig. 3, Fig. 7 a section on the line 7—7 of Fig. 1, and Fig. 8 a detail view of the latch 32.

5 It will be understood that my invention is applicable to different kinds of furniture such as davenports, bed couches and the like, but in the present instance I have shown the same embodied in a davenport for the purpose of giving a clear and definite description 25 of my invention and without intention of limiting myself thereto.

Referring to the embodiment of my invention as herein shown the davenport 30 comprises a stationary structure consisting of the two end pieces or frame members 1 connected together by a front cross-piece 2, the back-piece 3 and cross bar 4,—or otherwise as desired,—and the back 6, and a seat 5 which is adapted to be rotated to an inverted position.

The seat 5 is mounted to rotate in suitable manner between the end frames and also adapted to have a sliding movement with re-

spect thereto. As clearly shown in the drawings the end frames are each provided with a horizontal bearing bolt 7 projecting inwardly of the frame and having its extreme inner end extending into a recess 8 formed in the adjacent end of the body of the seat 55 and extending longitudinally of such end. This bearing bolt also passes through a slot 9 registering with the recess 8 and formed in a bracket plate 10 which is secured to the end of the seat. It will be understood that each end of the seat is similarly constructed and provided with a bracket plate as just described. By reason of this mounting of the seat, the same is permitted to rotate and also have a sliding movement as required in 60 the opening and closing operations hereinafter described. Each bracket plate is provided at its rearward end with a depending portion 10^a from which projects laterally a bearing pin 11 having at its outer end an 65 enlarged head 11^a for purposes hereinafter described.

Each end frame is provided on its inner side with a curved track and in the present instance and by preference this track is 70 formed by means of a plate 12 secured to its end frame in any suitable manner. This plate is curved as shown in Figs. 1, 3 and 5 and provided with a curved slot 13 registering with a similarly curved groove or recess 75 14 in the body of the end frame. The adjacent pin 11 projects through the slot 13 and its head is received in the groove 14. The plates 12 as thus constructed have a trackway 80 on the end frames for the pins 11 which are thereby guided in the movements of the operating parts. The upper forward end of each slot 13 is provided with an offset 13^a in which its pin 11 is adapted to rest and be held in the open condition of the bed sections. These offsets have sockets whose bottoms 85 are below the points of junction between the slots and the sockets forming crests in the trackway, whereby the pins 11 remain in the sockets until positively raised 90 by the operator and forced rearwardly over such crests into the slots. By placing the slotted plates 12 on the end frame members of the davenport they may be formed of 95 relatively large dimensions, as compared 100 with a structure in which trackway members are carried by the seat frame, and a stronger, more sightly, and more easily operable mech-

anism results. In the normal or closed condition of the davenport the pins 11 are positioned at the upper rearward end of the slots 13 as shown in Fig. 3 but in the opening movements of the parts each pin moves throughout the length of its slot, giving the required movement to the seat and attached parts as hereinafter explained.

The bed spring may be made in any number of folding sections and as herein shown the same comprises three main sections indicated generally by the reference letters A, B and C and two short sections indicated by the reference letters *a* and *b*, the section *a* being located between and pivotally connected with the main sections A and B and the section *b* being located between and pivotally connected to the main sections B and C, all as clearly indicated in Fig. 2. The bed spring may be of any suitable construction, in so far as the fabric thereof is concerned, but its side rails, which are here shown as made of angle iron, are made in sections corresponding to the sections named for folding purposes. The main sections A, B and C have side rails 15, 16 and 17 respectively and the short sections *a* and *b* have similar but shorter rails 18 and 19 respectively. The rails 18 are pivotally connected at their ends to the rails 15 and 16 respectively and the rails 19 with the rails 16 and 17 respectively.

The innermost section A of the bed spring is connected with the bottom of the seat in pivotal manner and has a parallel ruler motion with respect thereto. For this purpose this section A is not connected directly with the under side of the seat 5 but indirectly by means of the parallel links 20, one at each end of the seat and each pivotally connected at its ends to the seat and to the rails 15 respectively. At each inner corner of the seat as shown in Fig. 3 there is provided a depending bracket 21 which in connection with a second depending bracket 22, shown in detail in Figs. 6 and 7, provide a bearing for the pivot pin 23 passing through the side rail 18 at each end of the section *a* at a point intermediate its length and in the present instance midway thereof. The brackets 21 and 22 are here shown as two separate parts but it will be understood that they might be made as an integral structure. One flange of the adjacent rail is adapted to pass between the outer ends of the two brackets and to be pivotally supported therebetween on said pivot pin 23 as is clearly indicated in Figs. 6 and 7. By reason of the described construction the bed spring is pivotally connected to the seat and is capable of being raised therefrom when the sections are extended, as shown in Fig. 1.

The front end of the seat 5 is provided with a depending panel 24 which is secured

thereto and movable therewith. This panel is adapted to close the space at the front of the davenport below the seat when the parts are in the normal or closed position, shown in Fig. 3. In order to lock the folded sections together upon the seat during the operation of the parts this panel is provided on its inner side with a lock which consists of a hook 25 extending inwardly and pivoted upon such panel within the clips 26 secured thereto. When the hook 25 is turned inwardly, as shown in Figs. 3 and 5, it projects in the path of movement of a pivoted cross-bar or bail 27 with the result that the folding sections of the bed are held in closed relationship with respect to the seat both in the open position shown in Fig. 5 and in the closed position shown in Fig. 3, in which latter position this hook acts as a support for the folded sections. The panel 24 in its closed position is adapted to rest upon the cross-piece 2 of the davenport, as shown in Fig. 3.

The bed section B is provided at its opposite sides with the legs 28 and the bed section C with legs 29. The legs 28 are pivoted to the rails 16 near their upper ends and the extreme upper ends thereof have pivotally connected thereto the links 30 whose forward ends are pivotally connected to the rails 18, with the result that when the bed sections are folded these legs will be automatically folded along side of the rails 16. The legs 29 are similarly pivoted to the rail 17 and provided with links 31 whose inner ends are pivotally connected to the rails 19 whereby the same automatic folding of such legs is effected in the folding operation of the sections. By preference the legs 29 are provided with pivoted latches 32 each of which is normally held in horizontal position against the pin 33 by means of the spring 34, upward movement of the latch being limited by the stop pin 35. Each latch is adapted to hook over a pin 36 extending laterally from a side rail 16 as clearly indicated in Fig. 3.

Describing the preferred operation of the davenport and assuming that the parts are in their normal or closed position as shown in Fig. 3, and it is desired to open the same, that is convert it into a bed, the first step consists in partially rotating the seat 5 and consequently all of the bed sections attached thereto until they assume a practically vertical position with the pins 11 at the lowermost point in their track-ways. The bed sections are now unlocked by swinging the lock 25 so as to release the bail 27 and the bed sections are simultaneously unfolded and drawn outwardly away from the davenport frames, with the result that the seat 5 will, by such action be further rotated until it is completely reversed whereupon the pins 11 will enter and be retained in the offsets

33^a. In this unfolding and withdrawing movement of the bed the last section C may be left folded upon the section B until the latter is extended to horizontal position 5 whereupon such section C may then be unfolded and brought to a horizontal position. In the act of unfolding the bed sections, the section A will automatically rise to a position above the bottom of the seat which is 10 now uppermost, such position being indicated in Fig. 1. It will also be understood that the legs 28 and 29 automatically assume their position in folding and unfolding 15 of the bed sections. If desired the bed may be folded and closed by steps just the reverse of those already explained but for convenience in manipulation it is preferred to fold up the bed sections and to lock them upon the seat in the manner indicated in 20 Fig. 5 and to then lift such parts including the seat upwardly and move it forwardly so as to disengage the pins 11 from the offsets 13^a, whereupon all of these parts are free to be returned to the normal condition illustrated in Fig. 3.

It is obvious that my structure may be made of any suitable material or materials found expedient or desirable, and while I have shown the end frames and seat for instance as made of wood, the same may be made of metal, in which event the slotted plates thereof could be made integral. Moreover, while I have herein shown three 35 main sections of bed springs it will be evident that the number thereof may be varied, for instance, the outermost section C and small section b may be dispensed with, in which case the length of the bed would correspond in direction with the length of 40 the davenport, whereas when the full number of sections shown is used, the length of

the bed would be transverse of the length of the davenport.

I claim:

1. In furniture of the class described, the 45 combination of stationary end frame members having on their inner sides trackways consisting of curved slots, said slots curving upwardly from the center and the front ends of such slots extending sharply downward over a crest in each trackway to form offset sockets, a seat mounted to rotate in the frame members, sliding pivot members carried by said seat coacting with the slots and arranged to rest in the sockets when the 50 seat is in inverted position, whereby said pivot members remain in the sockets until positively raised and forced rearwardly past the crest in the trackway.

2. In furniture of the class described, the 60 combination of stationary end frame members having on their inner sides trackways consisting of curved slots, said slots curving upwardly from the center and the front ends of such slots extending sharply downward over a crest in each trackway to form offset sockets, a seat mounted to rotate in the frame members, bearing brackets secured to the ends of the seat, bearing members intermediate said stationary frame members 65 and said bearing brackets whereby the seat is mounted to rotate, sliding pivot members carried by said bearing brackets coacting with the slots and arranged to rest in the 70 sockets when the seat is in inverted position, whereby said pivot members remain in the sockets until positively raised and forced rearwardly past the crest in the trackway.

SAMUEL GOLDSTEIN.
